DESIGN FOR A SALT OR PEPPER SHAKER

Frank Kafka, New York, N. Y., assignor to Krest
Manufacturing Co., New York, N. Y.

Application August 11, 1934, Serial No. 52,920

Term of patent 3½ years

To all whom it may concern:

Be it known that I, Frank Kafka, a citizen of the United States residing at 329 East 29th Street, New York city, in the county of New York and State of New York, have invented a new, original, and ornamental Design for a Salt or Pepper Shaker, of which the following is a specification, reference being had to the accompanying drawing, forming part thereof:

I claim:

The ornamental design for a salt or pepper shaker as shown and described.

FRANK KAFKA.
